UNITED STATES PATENT OFFICE

114,590

DESIGN FOR A DRESS ENSEMBLE

Leo Jacobson, New York, N. Y.

Application March 25, 1939, Serial No. 83,837

Term of patent 3½ years

To all whom it may concern:

Be it known that I, Leo Jacobson, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my design;

Fig. 2 is the rear view thereof;

Fig. 3 is a front view of the dress of the ensemble as shown in Figs. 1 and 2, and

Fig. 4 is the rear view thereof.

I claim:

The ornamental design for a dress ensemble, substantially as shown.

LEO JACOBSON.
